MOLD FOR CASTING CRANKSHAFTS

Howard W. Miner, Beloit, Wis., assignor to Fairbanks, Morse & Co., Chicago, Ill., a corporation of Illinois

Application January 7, 1949, Serial No. 69,659

1 Claim. (Cl. 22—134)

1

This invention relates to the casting of irregular shaped objects, such as crankshafts and the like, and one of the important objects is to improve upon the method of casting and the technique for arranging a mold for casting such objects.

It is also an important object to provide improvements in the method of and arrangement for gating and risering the casting mold cavities to obtain a uniform flow and deposit of the casting metal, and assure an adequate supply of casting metal to compensate for shrinkage during solidification.

Another object of the invention resides in the improved technique of supplying casting metal to the risers to avoid undue agitation of the molten metal collecting in the mold cavities, and to the further technique of maintaining the fluid condition of the casting metal in the risers at least until the solidification and shrinkage of the metal has occurred in the mold cavities.

Other objects and advantages of the invention will become obvious from the detailed description relating to certain preferred embodiments hereof, the same being disclosed in the accompanying drawing, wherein:

Fig. 1 is a longitudinal sectional elevation, through a mold assembly for casting a crankshaft, and in which the cavities and risers are shown to advantage;

Fig. 2 is a top plan view of the lower or drag portion of the mold of Fig. 1;

Fig. 3 is a bottom view of the upper or cope portion of the mold of Fig. 1, showing the arrangement and disposition of runners, gates and risers;

Fig. 4 is a sectional elevational view taken at line 4—4 of Fig. 1;

Fig. 5 is a transverse sectional elevational view of a somewhat modified arrangement of mold assembly;

Fig. 6 is a top plan view of the lower or drag portion of the mold of Fig. 5; and,

Fig. 7 is a bottom view of the upper or cope portion of the mold assembly shown by Fig. 5, and in which the arrangement of runners, ingates and risers have been clearly indicated.

In Figs. 1 and 4 of the drawing, the mold assembly is seen to include a cope 10 and a drag 11 longitudinally divided in the plane of the crankshaft axis, so that parts of the mold cavities which define the crankshaft article to be cast are located in each of the cope and drag portions of the mold. More specifically, the cavities formed in the drag 11 have been shown in Fig. 2, while those in the cope are clearly illustrated in Fig. 3. It is understood that the cavities in the sand of the cope and drag are formed by packing and ramming sand about the cope and drag patterns and then withdrawing the patterns. In the following descrip-

2

tion of the mold assembly, the matching parts of the cavities in the cope and drag will be identified by similar reference numerals, since such cavity portions cooperate to form a complete cavity in which solid portions of the crankshaft are produced.

In the above referred to views, the crankshaft cavities include the end bearing cavity 12 flanked by enlarged flange cavities 13 and 14, an opposite end bearing cavity 15 having a series of stepped diameter zones decreasing toward the free end, and a plurality of spaced, intermediate crank bearing cavities 16, 17, 18, 19, 20 and 21. Between the bearing cavities 15 and 16, a pair of spaced crank cheek cavities 22 and a crank pin cavity 23 have been provided. In a similar manner, pairs of crank cheek cavities 24, 25, 26, 27 and 28 are provided, and each such pair is connected by respective crank pin cavities 29, 30, 31, 32 and 33. The casting of a one-piece crankshaft is rendered difficult due to the respective angularities of the several crank throws which, as may be seen in Fig. 1, places certain of the cavities substantially wholly in the cope 10 and others in the drag 11.

It is an important feature of the present improvements to provide a system of mold runners, ingates, risers and the like which will permit the introduction of the molten casting metal to all of the mold cavities in a manner tending to produce a more perfect article. In Fig. 3, which is a bottom face view of the cope 10, the molten metal is first conducted through a plurality of sprues 35, four being shown and located in pairs at the opposite ends of the mold. One sprue 35 in each pair is connected by a longitudinally extending runner passage 36, so that the molten metal may be introduced simultaneously from opposite ends of the mold and at each side of the mold cavities. From each of these runners 36, a plurality of ingate channels lead to the various cavity zones, it being particularly noted that the ingates are directed for feeding molten metal into the cavities so that the metal is as near as possible to the riser openings. In the view of Fig. 3, the upper runner 36 is connected to the mold cavity spaces by a series of ingates 37, 38, 39, 40, 41, 42 and 43; with the ingates 37, 38 and 39 feeding the large flanged bearing cavity 12, ingates 40, 41 and 42 feeding respectively the crank pin cavity 33 and crank cheek cavities 26, and ingate 43 feeding the opposite bearing cavity 15. The opposite longitudinal runner 36 is connected with the cavity 12 and its flange cavities 13 and 14 by ingates 45, 46 and 47. Also, this lower runner 36 connects with the crank pin cavity 30 by the ingate 48, with the crank cheek cavities 24 by ingates 49 and 50, and with the cavity 15 by the ingate 51.

In conjunction with the system of runners and

ingates above noted, the mold cope is formed with shrinkage make-up reservoir means in the nature of a series of enlarged riser openings (Fig. 1) which communicate with the mold cavities at or close to the high zones thereof. For example, riser 53 opens to cavity 13, riser 54 opens to cavity 12, riser 55 opens to cavity 14, risers 56, 57 and 58 respectively open to crank pin cavity 32 and the adjacent cheek cavities 27, to cavity 31, and to cavity 30, and riser 59 opens to the cavity 15. The connecting ports or openings from these risers have been indicated in Fig. 3, and may be identified by reference numerals having the suffix *a*. In addition to these risers, the cope also provides other risers (not shown) which connect with and open to the pin cavity 29 at opening 60*a* and to the pin cavity 33 at opening 61*a*. The general relation of riser and riser opening to a mold cavity is illustrated in Fig. 4, in connection with the sectional view of riser 55 in Fig. 1.

The described system of runners, ingates and risers provides a flow of molten casting metal to all of the mold cavities substantially uniformly and together, enables the feeding of the lowest cavity areas which tends to maintain a uniform level of molten metal and reduces appreciable endwise flow disturbances, and the upper riser connections permit rapid and complete venting of the mold cavities whereby the molten metal may fill up such zones as the general level of casting metal rises to and begins flow into the several risers, which collectively constitute the reservoir means.

It is a further preference in the present method and technique of casting, to establish characteristics of directional solidification of the casting metal so that the final article may be free of imperfections at any part throughout its length. Such imperfections heretofore encountered, have usually been occasioned by imperfect venting of the cavities, too rapid chilling of the metal in certain mold cavities or zones, disturbances in the flow of casting metal between cavities, and improper feeding of the metal from the risers back to the mold cavities during solidification shrinkage. These usual difficulties have now been obviated by the application of directional solidification within the mold cavities, and by means enabling the maintenance of fluidity of the casting metal in the risers such that the same may be free to feed back to the mold during shrinkage, without restriction at the riser openings.

The directional solidification of the casting metal is cared for by the use of metallic chills located in the surfaces of certain mold cavities in such positions as to be contacted by the incoming molten metal and immediately extract the heat therefrom to initiate solidification. The use of chills has already been suggested, however such prior use has been to position the chills near the central zone of a mold cavity to initiate internal solidification ahead of any solidification taking place at the outer surfaces of the mold cavity. As a consequence, the chills become a part of the final casting, being completely embedded in the casting, and in some cases fusing into the casting metal. In the present case, the chills are not so employed to initiate chilling or solidification at internal zones of the casting, and as such do not become a part of the final product. By preference, the chills are positioned in the mold sand to provide heat absorbing zones in the surfaces of the mold cavities, and to initiate solidification of the casting metal from the low points of the mold cavities. In this manner, the

object to be cast is caused to begin its solidification in its lowest areas, and the solidification progresses toward the risers where the still fluid metal may freely feed back to the cavities to compensate for shrinkage and maintain the cavities completely filled throughout the process of solidification.

In the example illustrated in Figs. 1 to 4, the outer surfaces of the several mold cavities have been provided with embedded chills, and these chills have been located to attain the desired directional solidification of the casting metal. A representative case of the present use of chills may be observed in Fig. 4, wherein the lower or drag surfaces of the mold cavity 14 have embedded metallic chill elements 14*c*. In each instance where a mold cavity is provided with embedded chills, as in Figs. 1, 2 and 3, the chill or chills have been identified by the numeral designating the cavity with the addition of the suffix letter *c*. It is believed that this will obviate any further detailed reference to the chills.

A further feature hereof resides in the means for prolonging the fluidity of the casting metal in the several mold risers 53, 54, etc. Referring to Figs. 1 and 4, it will be observed that the walls of the riser 55 are provided with and are defined by embedded insulation blocks or elements 55*b*. In each instance, the insulation blocks associated with the respective risers 53, 54, etc. have been indicated by the suffix letter *b*. These blocks may be formed of any suitable material which will stand up under direct contact by the high temperature molten metal, and it is preferred that the several blocks for each of the risers extend over a maximum vertical height of the riser so that the volume of metal therein may be maintained in a fluid state until the solidification in the mold cavities has progressed into the riser bottom openings. It is also important to prevent premature or untimely solidification within each riser to preclude any obstruction forming in the riser openings 53*a*, 54*a*, etc. which could cause or result in incomplete feed back during shrinkage, or shrinkage breakaway of the metal neck in these openings.

This last consideration is prevented by the improved technique of boosting or increasing the temperature of the riser metal following completion of the pouring step and after the general level of casting metal in all of the risers has become established. Prior technique has involved the step of adding a quantity of molten metal to each riser from the original ladle or by use of hand ladles. This prior technique is commonly referred to as "riser touch-up," and when carried out in the usual manner results in a pronounced disturbance of the metal in the mold due to the gravitational unbalancing of the level of metal between risers and from end to end of the mold. The presently improved method is to deposit a suitable quantity of thermite on the surface of the metal in each riser. This thermite may be ignited by a primer material, in the usual manner, and upon ignition imparts a sudden charge of heat to the riser metal whereby to boost its temperature. The use of thermite, which is a well known compound, has the important advantages that it does not disturb the level of the metal in any of the risers, and may be applied quickly and easily. Thus the combination of insulating the risers by the block elements 53*b*, 54*b*, etc., and the application of thermite to boost the temperature of the riser metal will result in maintenance of the fluidity

of the metal until the mold cavities have become completely filled out and all shrinkage has been compensated.

The above described method and technique of casting is excellently suited to large articles, and has been carried out successful in the production of large crankshafts. When applied in the casting of smaller articles, the same general principles may be followed with certain modifications, as will now be described in connection with the disclosure of a single throw crankshaft of Figs. 5, 6 and 7. In these latter views, the mold drag 65 contains portions of the cavities, and the mold cope 66 contains the remainder of the cavities together with the sprue, ingates and reservoir means or riser. Following the same system of indicating the cooperating portions of the cope and drag cavities by similar reference numerals, it can be seen that the article to be produced is characterized by such mold cavities as the end bearing cavities 67 and 68, spaced crank cheek cavities 69 and a crank pin cavity 70. The mold drag 65 also contains the riser pocket 71 and the lower part of the runner opening 72, whereas, the mold cope 66 is provided with the sprue 73 leading from the pouring box 74 to a longitudinal runner passage 75. The runner 75 connects with the end bearing cavity 67 at spaced zones by means of ingates 76 and 77, and with the opposite cavity 68 by ingates 78 and 79. The mold cavity 70 is connected to the riser by means of the runner opening 72, it being clear that the complete riser is constituted by the respective drag and cope portion 71 and 81.

During pouring, the molten metal substantially simultaneously flows into the cavities 67 and 68, and this, it will be observed, establishes the general flow trends from the end zones of the cavities 67 and 68 toward the crank cheek cavities 69, and finally into the pin cavity 70. Since the molten metal is fed thereto at a number of ingates, it can be appreciated that very little endwise flow disturbances can occur in the cavities 68 and 69, except that which is due to the ordinary and slow shrinkage process during solidification. The riser pocket 71 is by preference, given a sufficient volumetric capacity to regulate its filling with molten metal in time with the filling of the mold cavities, so as to provide ample opportunity for venting of such cavities to the riser portion 81 through the runner opening 72.

As the pouring continues, the level of the metal will eventually rise above the opening 72 and, as this takes place, the metal in the runner 75 will back up and seek a flow path through the auxiliary passage or up-gate 82 (Fig. 5) where it may enter the upper zone of the riser 81. The provision of up-gate 82 allows a direct flow of hot metal onto the riser metal to maintain or boost its temperature for prolonged fluidity. Thus no riser touch-up is required to boost the temperature of such metal, and the gravitationally quiescent condition of the metal in the mold cavities is preserved during the solidification process. Further retention of the heat of the metal in the riser 81 is obtained by the use of a number of blocks 83 of insulation in the riser walls, as indicated in Figs. 5 and 7.

It should now be apparent that the essential features of rapid feeding of the mold cavities from a plurality of ingates leading to the low zones of such cavities, minimization of endwise flow of molten metal, prevention of disruptive

endwise flow disturbances by preserving gravitational balance of the metal level, and maintenance of fluidity of the casting metal in the reservoir means or risers by insulating the same and by imparting thereto a temperature boost, is fully carried out in the preferred forms of the mold assembly shown by Figs. 1 to 4 or by Figs. 5 to 7. Having now fully and clearly described the features of the present invention, it should be understood that the method or technique in practicing the invention shall be limited only in accordance with the scope of the following claim.

I claim:

In a mold for horizontal casting of crankshafts, the combination of a mold drag section having a pattern impression of the crankshaft to be cast, arranged horizontally therein such that the longitudinal center line of the crankshaft lies substantially in the plane of the face surface of the drag section, and a mold cope section having a pattern impression of the crankshaft complementary to the impression in the drag section, the drag and cope pattern impressions forming a horizontal, communicating series of molding cavities to receive the casting metal; the cope section being provided with runner passages extending longitudinally thereof on opposite sides of the series of molding cavities, vertical sprue passages opening to the opposite ends of each runner passage, vertical riser passages individual to certain of the molding cavities, each communicating at its lower end with the associated molding cavity substantially in the uppermost zone of the cavity, and opening at its upper end through the top surface of the cope, and a plurality of ingate passages relatively spaced along each runner passage and extending horizontally therefrom to communication with said series of molding cavities, certain of said ingate passages leading directly to certain of said molding cavities having riser passages associated therewith and opening to such cavities in zones thereof relatively near the zones of cavity communication of the riser passages; said riser passages providing for the escape of gases from the molding cavities in crankshaft casting, and serving as reservoirs for the accumulation of excess casting metal rising therein from the molding cavities, and insulation means embedded in the interior surfaces of the riser passages to prolong fluidity of the excess casting metal accumulated in the riser passages, until solidification of casting metal in the molding cavities is substantially complete.

HOWARD W. MINER.
